[57] CLAIM

The ornamental design for a golf shoe brush, as shown and described.

DESCRIPTION

FIG. 1 is a right side elevation view of the invention;

FIG. 2 is a rear elevation view of the invention;

FIG. 3 is a top plan view of the invention;

FIG. 4 is a left side elevation view of the invention;

FIG. 5 is a front elevation view of the invention; and,

FIG. 6 is a bottom plan view of the invention.

The jagged lines shown on the head of the brush in FIG. 1 are understood to represent the type of bristles as shown in FIGS. 2, 3, 5 and 6.
